UNITED STATES PATENT OFFICE.

MAURICE HOFHEIMER, OF NEW YORK, N. Y.

STREET-SIGN.

SPECIFICATION forming part of Letters Patent No. 770,068, dated September 13, 1904.

Application filed March 24, 1904. Serial No. 199,823. (No model.)

To all whom it may concern:

Be it known that I, MAURICE HOFHEIMER, of New York, in the county of New York and State of New York, have invented certain new and useful Improvements in Street-Signs; and I do hereby declare the following to be a full, clear, and exact description of the invention, such as will enable others skilled in the art to which it appertains to make and use the same.

10 The object of this invention is to provide an improved sign which shall be visible by day and in which the names of streets or other indications may be illuminated at night by an electric lamp or other source of light without diverting any material part of such light which is ordinarily used for other purposes.

15 Furthermore, my invention has for its object to provide a sign specially adapted for posts carrying overhanging lights, the rays whereof will be directed and diffused through each of several sign-boards.

20 The invention will be hereinafter fully set forth, and particularly pointed out in the claims.

25 In the accompanying drawings, Figure 1 is a view in perspective, showing my invention applied to a lamp-post. Fig. 2 is an enlarged plan view. Fig. 3 is a side elevation with parts in vertical section. Fig. 4 shows a slight

30 modification.

35 The invention may be embodied in any desired style of sign-frame, which may be cylindrical, triangular, or of any shape which its various uses may dictate. In the present instance I have shown the frame of rectangular formation, consisting of sides 2, which are joined together by corner-pieces 3. The frame is supported by a series of brackets 4, the inner ends of which are clamped to the electric-40 light post 5, which latter supports an overhanging lamp 6. The sides 2 of the frame are formed with longitudinal openings to provide clear spaces for the display of sign-boards 7, which are placed immediately back of said

45 openings, being secured at their ends in grooves 8 and supported at their bottoms by inwardly-extended lugs 9. The grooves 8 are preferably formed on the inner faces of the sides 2. These several sign-boards may be made

50 of any material in which part of the surface

is transparent or translucent and the remaining surface more or less opaque, except in the instance hereinafter described. Porcelain may be used or stenciled metal or colored glass, with the letters etched out or sand-blasted. 55 Behind two of the sign-boards—namely, those nearer to or facing the source of light—are placed reflectors 12, which latter may preferably be made of white enameled plates or other suitable material, the white surfaces reflecting and at the same time diffusing the light. The ends 13 of these reflectors rest upon lugs 14 and are held in place by bearing against fingers 15, said lugs and fingers projecting inwardly from the corner-pieces of the 60 frame. The two remaining sign-boards—namely, those farther away from the light—are at a more or less oblique angle to the direction of the light, so that the rays of the latter will pass directly through them. 70

75 The sign-frame is attached to an electric-light post in about the position shown in Fig. 1 so that the light from the lamp will strike directly upon those two signs which are farther away from the light and upon 80 the reflectors of those two signs nearer thereto, as shown by the dotted lines A and B, Fig. 3, and C, Fig. 2. Thus the rays A will strike the reflectors 12 and will be reflected through the contiguous sign-boards in rear of which 85 they are located, while the remaining two sign-boards are in the unobstructed path of the rays B, so that the latter will pass directly through such sign-boards and illuminate them.

85 The scope of the invention clearly admits of numerous structural modifications, as well as in the purposes for which the signs may be employed.

In Fig. 1 I have shown the sign-frame as 90 attached to a post where the lamp is hung close to the body thereof, in which position very little of the light strikes directly upon the faces of the signs nearer thereto. The invention may be used as well in cases where 95 the lamp is located farther away from the post, as indicated in Fig. 4. In this instance the rays of light D will strike the faces of the two sign-boards nearer thereto, which now act as reflectors, while the rays E will pass 100

through the remaining sign-boards the same as in the first instance described. In this arrangement the reflectors 12 can be dispensed with.

5 I claim as my invention—

1. In combination with a post having an overhanging light, a sign-frame mounted on said post and having a plurality of separate signs, and means for reflecting the light from 10 the rear through the sign or signs facing in the direction of the light, the remaining sign or signs being in the unobstructed path of the light-rays which pass directly through them.

2. In combination with a post having an 15 overhanging light, a rectangular sign-frame mounted on said post, reflectors directly in rear of those two signs nearer to or facing the light for reflecting and diffusing the light through such signs, the remaining signs being 20 in the unobstructed path of the light-rays which pass directly through them.

3. In combination with a post having an 25 overhanging light, an open top frame secured to said post, signs in the sides of said frame, and reflectors in rear of and in close juxtapo-

sition to the signs nearer to or facing the light, the remaining signs being in the unobstructed path of the light-rays which pass directly through them.

4. The sign-frame having openings in its 30 sides, signs coincident with said openings, said frame having grooves at the ends of said openings on the inner sides to accommodate said signs, and supports for the latter consisting of lugs projecting inwardly from the frame near 35 the bottom thereof, as set forth.

5. The rectangular sign-frame having openings in its sides, signs fitted over said openings, reflectors in rear of some of said signs, lugs projecting inwardly from the frame for 40 supporting said reflectors, and fingers at some of the corners of the frame against which the ends of said reflectors are designed to bear.

In testimony whereof I have signed this specification in the presence of two subscribers. 45

MAURICE HOFHEIMER.
